UNITED STATES PATENT OFFICE.

JAMES MORRISON, OF TORONTO, CANADA.

INJECTOR.

SPECIFICATION forming part of Letters Patent No. 514,093, dated February 6, 1894.

Application filed May 18, 1893. Serial No. 474,642. (Model)

To all whom it may concern:

Be it known that I, JAMES MORRISON, of the city of Toronto, in the county of York and Province of Ontario, Canada, have invented a certain new and useful Improvement in Injectors, of which the following is a specification.

My invention relates to an improvement upon what is known as the Hancock inspirator, and the object of the invention is to provide simple and effective means by which the operating valves are controlled by a single lever, and it consists, in the peculiar construction, arrangement and combinations of parts hereinafter more particularly described and then definitely claimed.

In the accompanying drawings—Figure 1, is a sectional elevation of my improved injector with the steam valves closed. Fig. 2, is a similar view with the steam valves open. Fig. 3, is a detail showing the manner of connecting the steam valves to the sliding stem.

Referring now to the details of the drawings by letter, A represents a hand lever pivoted to the post B, the latter being secured to the casing B' of the injector. The casing B' is preferably made of two parts b b' connected together by the passage-ways N N'. Each of these two parts b b' is also divided into two parts, the divisions being formed by the valve seats H H, the latter being on the same plane with each other. Sliding over these valve seats H H are two valves F F which are secured by the pins G to the stem C, the latter passing through both parts b b' of the injector and through the stuffing box D and is pivotally connected to the hand lever A. On reference to Fig. 1, it will be noticed that when the valve in part b is centrally over the orifice I the other valve is set eccentrically over the orifice I' in part b'; thus allowing steam to pass through the orifice I' before the orifice I is uncovered. The upper end of part b' is arranged to receive fittings to connect with the steam supply while the lower end of said part b' is the inlet for the water. The passage-way N' which connects the parts b b' is continued through into the lower end of part b' and is turned upwardly and extends up to the bottom of the orifice I' in valve seat H. At the lower end of part b is the outlet for the water and from this outlet

is an annular projection n which extends nearly up to the orifice I. From the side of this same part b is the overflow M, which is arranged to be opened and closed by a valve L on the end of the sliding stem J which stem is connected to the lower end of the hand lever A.

The operation of my device is as follows: The hand lever A is moved slightly outward sufficiently only to open the orifice I', allowing the steam to enter said orifice and pass through the passage-way N' to the overflow, thus producing the necessary vacuum to lift the water into the injector. When the water is raised so far that it flows through the overflow, the hand lever A is moved to the end of its stroke, thereby moving the valve F from the orifice I, so as to admit steam and force the water through said orifice, and simultaneously the inward movement of the sliding stem J closes the overflow valve L, thus putting my injector into complete action by the movement of a single lever.

What I claim as new is—

1. In an injector, a two-part casing, a passage-way connecting said two parts, a slide valve in each of said parts arranged to open and close the steam ports, a sliding stem passing through said two parts and having said valves secured thereto by pins projecting from their backs, a second stem passing into said injector and having a valve thereon to open and close the overflow, a post projecting from said casing between said stems, and a hand lever pivoted to said stems and post, whereby a single movement of said lever simultaneously moves all of said valves, substantially as described.

2. In an injector, a two-part casing, a passage-way connecting said two parts, a valve seat in each of said parts, a stem having two valves independently secured thereto on the same plane with each other and adapted to slide over said valve seats, the valves being so arranged that one is partly open while the other is shut, substantially as described.

3. In an injector, a two-part casing, a passage-way connecting said two parts, a valve seat in each of said parts arranged on the same plane with each other, a sliding stem extending through each of said parts, a valve in each of said parts, each of said valves se-

- cured to said stem and so arranged that one of them is partly open while the other is entirely shut, a second stem passing into said casing and arranged to open and close the 5 overflow port, in combination with a hand lever connected with and pivoted between said stems, whereby a single movement of said lever will simultaneously move all of said valves, substantially as described.
- 10 4. In an injector, a casing consisting of two parts b b' , a passage-way N' connecting said two parts, a valve seat in each of said parts on the same plane with each other, a sliding stem passing into each of said parts and having valves secured thereto, arranged to open 15 and close the orifices in said valve seats, a

steam inlet on the upper side of said valves, a water inlet at the lower end of one of said parts, the lower end of the other part forming the water outlet and overflow, a valve controlling said overflow and a stem secured to said valve, in combination with a post B extending from said casing between the said stems, and a hand-lever pivoted to said stems and post, whereby a single movement of said 20 lever simultaneously moves all of said valves, substantially as described.

25 Toronto, May 12, 1893.

JAMES MORRISON.
